STRAIGHT BAR KNITTING MACHINE

Fritz Lambach, Tenafly, N. J., assignor to Robert Reiner, Inc., Weehawken, N. J.

Application May 6, 1948, Serial No. 25,396

30 Claims. (Cl. 66—82)

1

This invention relates to textile machines, and more particularly to straight bar knitting machines.

An object of the present invention is to improve on the construction and arrangement of the automatic regulating means for regulating the length of the loops knitted by the knitting implements of a straight bar knitting machine.

A further object of the present invention is to provide a straight bar knitting machine with automatic regulating means for regulating the length of the loops wherein the controlling means used for setting a predetermined length of the loops do not swing together with the oscillating regulating shaft connected to the needle bar, so that said controlling means may be readily actuated by a controlling apparatus of the knitting machine.

Another object of the present invention is to provide a straight bar knitting machine with regulating devices of simple construction which require only a single pattern chain control for the knitting of so-called "loose courses" which may have different lengths of the loops.

A further object of the present invention is to simplify the construction and control of the so-called rocker device of a straight bar knitting machine adjusting the length of loops in the heel portions and sole portions of a stocking blank of a full fashioned stocking.

With the above and other objects of the invention in view, the invention consists in the novel construction, arrangement and combination of various devices, elements and parts, as set forth in the claims hereof, certain embodiments of the same being described in the specification and being illustrated in the accompanying drawings forming part of this specification, wherein:

Fig. 1 is a somewhat diagrammatical front elevational view of a straight bar knitting machine according to the invention, wherein only those parts are shown which are necessary for the understanding of the invention.

Fig. 2 is a vertical sectional view taken on line 2—2 of Fig. 1.

Fig. 3 is a vertical sectional view taken on line 3—3 of Fig. 1.

Fig. 4 is a fragmentary sectional view similar to that shown in Fig. 3, wherein, however, the needle bar is adjusted in a different position.

Fig. 5 is a sectional view taken on line 5—5 of Fig. 1.

Fig. 6 is a front elevational view of the main regulating device shown in Fig. 5.

Fig. 7 is a sectional view taken on line 7—7 of Fig. 6.

2

Fig. 8 is a sectional view similar to that shown in Fig. 7, wherein, however, the parts of the regulating device are in a different position.

Fig. 9 is a somewhat diagrammatical fragmentary sectional view of the knitting machine illustrating a controlling apparatus for the control of adjustable setting elements of various regulating devices of the knitting machine.

Fig. 10 is a vertical sectional view taken on line 10—10 of Fig. 1.

Fig. 11 is a horizontal sectional view taken on line 11—11 of Fig. 10.

Fig. 12 is a front elevational view of the loose course regulating device shown in Fig. 10.

Figs. 13—15 are fragmentary sectional views similar to that shown in Fig. 10, wherein, however, the parts of the loose course regulating device are in different positions.

Fig. 16 is a front elevational view of the rocker regulating device of the straight bar knitting machine.

Fig. 17 is a top plan view illustrating the shifting device for shifting the main cam shaft of the machine during narrowing operations.

Fig. 18 is a fragmentary sectional view illustrating the connection between the rocker wing and one half of the shifting cam of the machine.

Fig. 19 is a perspective view of the rocker wing.

Fig. 20 is a vertical sectional view taken on line 20—20 of Fig. 16.

Fig. 21 is a vertical sectional view taken on line 21—21 of Fig. 16 wherein, however, the parts of the rocker device are in a position different from that shown in Fig. 20.

Figs. 22 and 23 are fragmentary sectional views similar to that shown in Fig. 20 wherein, however, the parts of the rocker device are in different positions.

Fig. 24 is an elevational view illustrating the rocker wing, the shifting cam, the brake and a portion of the controlling mechanism of the rocker regulating device.

Fig. 25 is a horizontal sectional view taken on line 25—25 of Fig. 24.

Fig. 26 is a perspective view of an element of the rocker regulating device, and

Fig. 27 is a diagrammatical view of a stocking blank.

Referring now to Fig. 1, 30 generally indicates the frame of a two-section straight-bar knitting machine. A motor 32 mounted on a bracket 34 carried by the frame 30 of the knitting machine is connected through a train of gears 36 with the main cam shaft 38 rotatably and shiftably arranged in suitable bearings of the frame of the machine.

40 generally indicates a pattern-chain carrying a series of buttons 42 (see Fig. 12) for the control of certain mechanisms of the knitting machine. During the operation of the machine, the pattern chain 40 is intermittently advanced in a manner known per se by a suitable mechanism actuated by a cam (not shown) keyed to the main cam shaft 38.

Fig. 1 illustrates only a few of the cams keyed to the main cam shaft 38. As viewed from the right to the left, the cams shown in Fig. 1 are: a first loose course regulating cam 44, a main regulating device cam 46, a presser arm cam 48, a needle bar cam 50, a second loose course regulating cam 52, rocker wings 54 and 56, shifting cam means 58, 60.

As best shown in Figs. 1-4, in each section of the knitting machine the needle bar 62 carrying a series of needles 64 is mounted on two needle bar hinges 66 and a needle bar presser arm 68.

Each of the needle bar hinges 66 is pivoted at 70 to a needle bar arm 72 secured to a needle bar shaft 74 rotatably arranged in suitable bearings of the frame. A spring-loaded needle bar cam follower 76 rigidly connected with the needle bar shaft 74 carries a roller 78 being in engagement with the needle bar cam 50 keyed to the main cam shaft 38.

Each of the needle bar presser arms 68 is pivoted at 80 to one end of a needle bar presser handle 82 having a recess 84 (see Figs. 3 and 4) normally engaged with a stud 86 arranged on one end of a presser arm 88, the other end of which is rigidly secured to a presser shaft 90 rotatably arranged in suitable bearings of the frame of the machine. A spring-loaded presser arm cam follower 92 rigidly connected with the presser shaft 90 carries a roller 94 arranged for engagement with the presser arm cam 48 keyed to the main cam shaft 38.

Apparently, if the presser shaft 90 were at a standstill, the needle bar cam 50 cooperating with the needle bar cam follower 76 would cause an upward and downward movement of the needles 64. Furthermore, if the needle bar shaft 74 were at a standstill, the presser arm cam 48 cooperating with the presser arm cam follower 92 would cause a movement of the needles 64 towards and away from the press edge 96 of the knitting machine. In fact, of course, during the operation of the knitting machine, the needle bar shaft 74 and the presser shaft 90 may be in movement at the same time, whereby the needles 64 are subject to a composite movement.

When the machine is at a standstill and it is desired to obtain ready access to the needles 64 for the performance of a necessary manipulation, the needle bar 62 may be swung into the position shown in Fig. 4 by disengaging the recess 84 of the needle bar presser handle 82 from the stud 86 and pushing the handle into the position shown in Fig. 4 wherein the stud 86 abuts against the shoulder 98 of the handle 82. After the manipulation on the needles 64 has been carried out, the recess 84 of the needle bar presser handle 82 may be re-engaged with the stud 86 as shown in Fig. 3, so that the machine is ready for further operation.

During the operation of the machine, the sinkers 100 reciprocated in a manner known per se by the slur cocks (not shown) are always advanced to the same extent, for example, into the extreme advanced position shown in Fig. 3. Therefore, the more the needles 64 are moved towards the press edge 96, at a certain moment

5 during the performance of their composite movement, the longer the length of the loops knitted by the knitting implements of the machine. In other words, the length of the loops to be knitted can be regulated by the degree of movement of the needles 64 towards the press edge 96.

The length of the loops of a stocking shall be different at different parts of the stocking. For example, the first loop course to be engaged with the welt hooks of the knitting machine shall have loops of a greater length than other courses of the welt. Furthermore, for example, the leg portion of the stocking shall be made of loops having a length smaller than other loops of the stocking, etc.

In order to regulate in a predetermined manner the length of the loops at various parts of the stocking, the knitting machine is equipped with regulating devices to be described hereinafter.

20 According to Figs. 1 and 3 a regulating shaft 102 rotatably arranged in suitable bearings of the frame of the machine carries an arm 104 rigidly secured thereto. Said arm 104 is in loose engagement with an adjustable set screw 106 arranged on the presser arm cam follower 92. The regulating shaft 102 may be oscillated during the operation of the machine in a manner to be described hereinafter. Obviously, the larger the degree of oscillation, the more the arm 104 is 25 swung to the right, as viewed in Fig. 3, and the more the needles 64 are moved towards the press edge 96 at a predetermined interval.

As best shown in Figs. 1 and 2, a spring-loaded stop arm 108 is rigidly secured to the oscillatable regulating shaft 102. Said stop arm 108 carries an adjustable stop screw 110 arranged for engagement with a rod 112 arranged in the frame of the machine. Upon an engagement of the stop screw 110 with the rod 112, the movement 30 of the regulating shaft 102 in counter-clockwise direction as viewed in Fig. 2 is limited.

As best shown in Fig. 1, four regulating devices are associated with the regulating shaft 102, i. e., as shown from right to the left, a first loose course regulating device generally indicated by 114, a main regulating device generally indicated by 116, a second loose course regulating device generally indicated by 118 and a rocker regulating device generally indicated by 120.

50 The main regulating device 116 shown in Figs. 1 and 5-8 comprises a block 122 rigidly connected with the regulating shaft 102 by means of a pin 124 inserted into registering bores of the block 122 and the regulating shaft 102. A cam follower 126 carrying a roller 128 cooperating with the main regulating device cam 46 keyed to the main cam shaft 38 is rigidly connected by means of a set screw (not shown) with a shaft 130 rotatably arranged in a bore of the block 122. A spring 129 stretched between the cam follower 126 and the rod 112 tends to urge the roller 128 against the cam 46 and to move a lug 131 on the cam follower 126 towards a stop pin 133 carried by the block 122 which is in the path 60 of said lug 131. The cam follower 126 has an extension 132 provided with three threaded bores 134a, 134b, 134c (see Figs. 6-8). An actuating screw 136a, 136b, 136c is adjustably threaded into each of said threaded bores 134a, 134b, 134c. A series of three plates 138a, 138b, 138c each carrying a pointer 140 for cooperation with a scale 142a, 142b, 142c is attached to the extension 132 by means of screws 144. Thus, each of said actuating screws 136a, 136b, 136c may be accurately adjusted on the extension 132, so that

a portion of a predetermined length of such a screw projects downward from the extension 132.

Furthermore, as best shown in Figs. 5 and 6 a member 146 provided with a series of bores 134d, 134e, 134f is rigidly connected with the rotatable shaft 130 by means of a screw 148, so that said member 146 participates in the rocking movements of the cam follower 126. An actuating screw 136d, 136e, 136f is adjustably threaded into each of the threaded bores 134d, 134e, 134f. Furthermore, a series of plates 138d, 138e, 138f, each of which carrying a pointer 150 is attached to the member 146 by means of screws 152. Each pointer 150 is arranged for cooperation with a scale 142d, 142e, 142f arranged on the actuating screws 136d, 136e, 136f, so that the latter may be accurately adjusted in such a manner that a portion of a predetermined length projects downwardly from the member 146. As best shown in Fig. 6, the actuating screws 136a, 136b . . . 136f are adjusted in such a manner that the portions of said screw projecting downwardly from the extension 132 of the cam follower 126 and from the member 146 are of different lengths for a purpose to be described hereinafter.

Each of said actuating screws 136a, 136b . . . 136f is arranged on the cam follower 126 and the member 146 rigidly connected therewith for cooperation with a spring-loaded latch 154a, 154b . . . 154f respectively. Said series of latches 154a, 154b . . . 154f is swingably and adjustably arranged on a shaft 156 carried by the block 122. A spring-loaded setting element 158a, 158b . . . 158f rockably arranged on the regulating shaft 102 is associated with each of said adjustable latches 154a, 154b . . . 154f. Each setting element 158a, 158b . . . 158f comprises a ring 160 rotatably arranged on the regulating shaft 102 and provided with a nose 162. Each nose 162 is arranged for cooperation with an associated spring-loaded adjustable latch 154a, 154b . . . 154f so as to set same in alternative positions in and out of the path of an associated actuating screw 136a, 136b . . . 136f. Furthermore, each nose 162 of the various setting elements 158a, 158b . . . 158f is arranged for cooperation with an abutting pin 164 carried by the block 122 so as to limit an extreme active position of the setting elements. Said abutting pin 164 serves also as a stop for the adjustable latches 154a, 154b . . . 154f so as to limit their inactive position wherein they are out of the path of the associated actuating screw 136a, 136b . . . 136f. Furthermore, the ring 160 of each adjustable spring-loaded setting element 158a, 158b . . . 158f is provided with a downwardly extending arm 166a, 166b . . . 166f respectively. Each of said downwardly extending arms 166a, 166b . . . 166f is pivotally connected with one end of a wire or rod 168a, 168b . . . 168f respectively.

As best shown in Fig. 9, the other end of such a wire or rod, for example, the wire or rod 168f is pivotally connected with the arm 170 of a spring-loaded cam follower 172 rotatably arranged on a shaft 174. The other arm 176 of said cam follower 172 is in engagement with a controlling cam 178 keyed to a control shaft 180 journaled in suitable bearings of the machine.

Said control shaft 180 and the series of controlling cams mounted thereon may be automatically advanced by the following actuating device: a control shaft cam 182 keyed to the main cam shaft 38 cooperates with a roller 184

carried by a spring-loaded cam follower 186 swingably mounted on a shaft 188. Said cam follower 186 has an arm 190 which is rocked downwardly and upwardly in accordance with the cam surface of the rotating control shaft cam 182. If the upwardly extending portion 192 of a controlling element 194 swingably mounted about a vertical pivot 196 in a block 198 is in the path of the arm 190 the block 198 will be rocked about the shaft 188 in accordance with a rocking movement of the arm 190 of the cam follower 186. A stop screw 200 arranged on the block 198 is normally urged against a rod 202 by means of a spring 204 acting on the block 198. The block 198 is pivotally connected at 206 with one end of a connecting rod 208, the other end of which is pivoted at 210 to an arm 212 of a ratchet wheel device generally indicated by 214. Thus, each rocking movement of the block 198 causes an advancing of the control shaft 180 through one step.

The position of above-mentioned controlling member 194 swingably mounted in the block 198 is controlled by a wire and rod connection 216 arranged in a manner known per se between the arm 218 and the controlling member 194 and a spring-loaded jack 220f, which is swingably mounted on a shaft 222 and actuated by a button on the pattern chain. When the spring-loaded jack 220f is actuated by a button of the pattern chain, the upwardly extending portion 192 of the controlling element 194 is swung into the path of the arm 190, so that the block 198 is rocked and the control shaft 180 is advanced by the ratchet wheel mechanism 214. As soon as the button of the pattern chain is past the jack 220f, the upwardly extending portion 192 of the controlling element 194 is swung out of the path of the arm 190 so that the arm 190 rocks idly and does not cause an advancing of the control shaft 180 through the ratchet wheel mechanism 214. As soon as another button on the pattern chain actuates again the jack 220f, the upwardly extending portion 192 is again swung into the path of the arm 190 for a further advancing of the control shaft 180 through the medium of the ratchet wheel mechanism 214. A more detailed description of the mechanisms for intermittently advancing the control shaft 180 and the set of controlling cams mounted thereon may be found in my co-pending patent application Serial #743,938 filed for "A Straight Bar Knitting Machine" on April 25, 1947, now Patent No. 2,574,487.

As may be readily understood from above in connection with Fig. 9, the setting element 158f is in the active position shown in full lines in said Fig. 9 wherein it sets the associated latch 154f in its active position in the path of the associated actuating screw 136f, as long as the arm 176 of the cam follower 172 is in engagement with a low part of the controlling cam 178. As soon as, however, owing to an advancing of the control shaft 180 and the controlling cam 178 mounted thereon through the medium of above-described mechanisms, the arm 176 of the cam follower 172 is engaged by a high portion of the controlling cam 178, the setting member 158f is swung into its inactive position shown in dash and dot lines in Fig. 9 through the medium of the wire 168f, whereby said setting element 158f causes the latch 154f to assume its inactive position likewise shown in dash and dot lines in Fig. 9 wherein said latch is out of the path of the associated actuating screw 136f.

It is understood that each of the remaining setting elements 158a, 158b . . . 158e is controlled by a controlling cam keyed to the control shaft 180 in the same manner as described above in connection with the setting element 158f controlled by the controlling cam 178. Consequently, each setting element 158a, 158b . . . 158f may be individually and selectively adjusted in an active or inactive position for setting the associated latch 154a, 154b . . . 154f in an active or inactive position as may be required for the knitting of the stocking.

According to Fig. 5, for example, the latch 154e is set by the setting element 158e in the inactive position wherein it is out of the path of the associated actuating screw 136e. The same is true of the position of the latch 154a in Fig. 7. When during a rotation of the cam 46 the roller 128 of the cam follower 126 is engaged by a high portion of said cam 46 as shown in Fig. 7, the cam follower 126 is swung from the position shown in Fig. 5 into the position shown in Fig. 7. During such a swinging movement of the cam follower 126 the latches 154 which are in their inactive position as is true, for example, of the latches 154e (Fig. 5) and 154a (Fig. 7) are not hit by the associated actuating screw 136, for example, the actuating screw 136e and 136a. Consequently, said actuating screws 136a, 136e do not have any influence on the latches 154a, 154f and the block 122 and the regulating shaft 102.

If, however, a setting element 158, for example, the setting element 158a is swung by an actuation of the controlling apparatus shown in Fig. 9 through the medium of the wire 168a from the inactive position shown in Fig. 7 into the active position shown in Fig. 8, the nose 162 of said setting element causes a swinging of the associated latch 154a from the inactive position shown in Fig. 7 into the inactive position shown in Fig. 8. Now, when the cam follower 126 is swung by the cam 46 from the position shown in Fig. 5 into the position shown in Fig. 8, the actuating screw 136a hits the actuating latch 154a in its path and causes a displacement thereof in downward direction. Said displacement of the latch 154a in turn causes a rocking of the block 122 from the position shown in Figs. 5 and 7 into the position shown in Fig. 8 through an angle α (see Fig. 8). Consequently, the regulating shaft 102 rigidly connected with the block 122 is rocked through the same angle α . Said rocking of said regulating shaft 102 may cause a rocking of the arm 104 (see Fig. 3) from the full line position into the dash and dot line position whereby the needles 64 are moved towards the press edge 96 from the full line position into the dash and dot line position. Upon a return movement of the cam follower 126 from the position shown in Fig. 8 into the position shown in Fig. 5 owing to a corresponding shape of the cam 46 and the action of the spring 129, the lug 131 of the cam follower 126 abuts against the pin 133 and causes the block 122 as well as the regulating shaft 102 to follow in counter-clockwise direction from the position shown in Fig. 8 into the position shown in Fig. 5.

It may be noted that above-described rocking movements of the regulating shaft 102 do not have an effect on the setting elements 158a, 158b . . . 158f which are loosely mounted on the regulating shaft 102 and may remain in their positions. In other words, the setting elements 158a, 158b . . . 158f of the regulating device ac-

7
8
cording to the invention do not participate in the rocking movements of the regulating shaft 102 and may be readily connected with a suitable controlling mechanism of the knitting machine, for example, with the controlling apparatus shown in Fig. 9.

Furthermore, as mentioned above and as shown in Figs. 5 and 6, the actuating screws 136a, 136b . . . 136f may be individually adjusted in such a manner that their end portions projecting downwardly from the extension 132 of the cam follower 126 and from the member 146 rigidly connected with the cam follower 126 are of different lengths. As will be readily understood, the longer said downwardly projecting end of such an actuating screw, the earlier it will hit the associated latch during a rocking movement of the cam follower 126 and, consequently, the larger the rocking angle α of the regulating shaft 102 and the larger the movement of the needles 64 towards the press edge 96 and the longer the length of the loops knitted by the knitting implements of the machine; on the other hand, of course, the shorter the length of the downwardly projecting ends of such an actuating screw, the later it will hit the associated latch, and consequently, the smaller the rocking angle α of the regulating shaft 102 and the smaller the length of the loops knitted by the knitting implements of the machine.

If, during the operation of the machine at any time two or more of the latches 154a, 154b . . . 154f are set in their active position, the actuating screw with the longest end projecting downwardly from the cam follower will hit its associated latch first and will determine the degree of the rocking angle α of the regulating shaft 102. Although some additional latches are in their active position, the associated actuating screws will not hit same, as said latches are mounted on the block 122 and follow the rocking movement of said block caused by the hitting of a latch by the actuating screw with the longest downwardly projecting end portion.

As shown in Fig. 1, the knitting machine is provided with a first loose course regulating device 114 and a second loose course regulating device 118. Said two loose course regulating devices are substantially of identical construction and it will be sufficient to describe hereinafter only the first loose course regulating device 114 in detail.

As best shown in Figs. 10 and 12 the loose course regulating device 114 comprises a block 224 rigidly connected to the regulating shaft 102 by means of a pin 226 passing through registering holes of the block and the regulating shaft. A spring-loaded cam follower 228 having a roller 230 cooperating with the loose course regulating cam 44 keyed to the main cam shaft 38 is swingably mounted at 232 on the block 224 in the same manner as above-described cam follower 126 of the main regulating device is swingably mounted on the block 122. The cam follower 228 has an extension 234 provided with a threaded bore 236a (see Fig. 12) and a member 238 having a threaded bore 236b is rigidly connected with the cam follower 228 so as to participate in the rocking movements thereof. In the embodiment shown in the drawings the member 238 is rigidly connected by means of a set screw 240 (see Fig. 10) with the shaft 232 rotatably arranged in the block 224 and rigidly connected with the cam follower 228 by a set screw (not shown). An actuating screw 242a is adjustably threaded into

the threaded bore 236a of the extension 234 of the cam follower 228 and an actuating screw 242b is adjustably threaded into the threaded bore 236b of the member 238. The actuating screw 242a cooperates with an adjustable spring-loaded latch 244a swingably mounted on a shaft 246 carried by the block 224; the actuating screw 242b cooperates with an adjustable spring-loaded latch 244b likewise swingably mounted on the shaft 246. The actuating screws 242a and 242b are adjusted in such a manner that, for a purpose to be described hereinafter, the downwardly projecting end of the actuating screw 242a is longer than the corresponding end of the actuating screw 242b projecting downwardly from the member 238.

The latch 244a may be set in and out of the path of its associated actuating screw 242a by means of a spring-loaded setting element 248a swingably arranged on the regulating shaft 102. The latch 244b may be set in and out of the path of the associated actuating screw 242b by means of a spring-loaded setting element 248b, likewise, swingably mounted on the regulating shaft 102. The setting elements 248a and 248b are substantially of the same construction as the setting elements 158a . . . 158f of the main regulating device described above in connection with Figs. 5-8. However, as shown in Figs. 10 and 12-15, a lip 250 is rigidly secured to the downwardly extending arm of the setting element 248b by rivets or the like. Said lip 250 projects from the downwardly extending arm of the setting element towards the downwardly extending arm of the setting element 248a in such a manner that said lip 250 may loosely engage said downwardly extending arm of the setting element 248a thus acting as a coupling element for a purpose to be described hereinafter.

The setting element 248a is controlled by a controlling cam 252 keyed to the control shaft 180 (see Fig. 1) through the medium of a wire 254 (see Figs. 10 and 12-15). One end of said wire 254 is pivotally connected with a cam follower (not shown but similar to the cam follower 172 shown in Fig. 9) cooperating with the controlling cam 252 on the control shaft 180. As shown in Figs. 10 and 13-15, the other end of said wire 254 has a slot 256 slidably engaged with a pin 258 carried by the downwardly extending arm of the setting element 248a. A spring 260 stretched between the wire 254 and a shaft 262 mounted on the frame of the machine tends to urge the wire 254 in right-hand direction as viewed in Fig. 10. The wire 254 thus connected with the setting element 248a through the medium of a pin and slot connection 256, 258 acts in conjunction with the controlling cam 252 mounted on the control shaft 180 as an automatic pre-selector, as will be described hereinafter.

The downwardly extending arm of the setting element 248b is pivotally connected with one end of a wire 264. As best shown in Figs. 10 and 11 the other end of said wire 264 is pivoted at 266 to an arm 268 of a bell-crank lever 270 swingably mounted at 272 on the frame of the machine. The other arm 274 of said bell-crank lever 270 is pivotally connected at 276 to one end of a wire 278. As shown in Figs. 10 and 12, the other end of said wire 278 is connected to a spring-loaded jack 220g swingably mounted on the shaft 222.

As long as there is no loose course knitted, the jack 220g is in the full line position shown in Fig. 12 and, consequently, the setting element 248b is in its inactive position shown in Fig. 10

wherein it sets the associated latch 244b in the inactive position out of the path of the actuating screw 242b arranged on the swingable cam follower 228.

If a loose course shall be knitted, the jack 220g is swung by a button 42 on the pattern chain 40 into the dash and dot line position shown in Fig. 12 whereby through the medium of the linkage 278, 270, 264, the setting element 248b is brought into the active position shown in Fig. 13 wherein it sets the latch 244b into the active position in the path of the actuating screw 242b.

Now, when at the time of such a movement of the setting element 248b into its active position, by a button on the pattern chain, the setting element 248a is held in its inactive position by the wire 254 as shown in Fig. 13 in accordance with the shape of the controlling cam cooperating with the wire 254, only the latch 244b controlled by the setting element 248b will be brought into the active position while the latch 244a controlled by the setting element 248a remains in its inactive position. Therefore, the regulating shaft 102 is rocked through a certain angle upon a displacement of the latch 244b by the actuating screw 242b arranged on the cam follower 228 so as to control a predetermined length of the loops in the loose course.

After the completion of such a loose course, the pattern chain 40 is advanced one step whereby the button previously displacing the jack 220g is disengaged from the jack and the latter returns into its normal position shown in full lines in Fig. 12. Said return movement of the jack 220g causes a return movement of the setting element 248b from its active position shown in Fig. 13 into its inactive position shown in Fig. 14 whereby the latch 244b is also returned into its inactive position shown in said Fig. 14.

As mentioned above, the link of the downwardly projecting end portion of the actuating screw 242b determines the length of the loop in the loose course. Now, if it is desired to knit a loose course with loops of greater length than the length determined by the adjustment of the actuating screw 242b the following operation takes place:

At a suitable interval the wire 254 controlled by the controlling cam 252 on the control shaft 180 is moved from the position shown in Fig. 13 wherein the right-hand edge of its slot 256 is engaged with the pin 258 of the setting element 248a into the position shown in Fig. 14 wherein the left-hand edge of its slot 256 is engaged with the pin 258. In spite of this movement of the wire 254, the spring-loaded setting element 248a is held at this time in its inactive position by means of the lip 250 loosely engaged with said setting element 248a but rigidly connected with the setting element 248b held in its inactive position by the wire 264. Yet, an automatic pre-selection of the setting element 248a has been carried out by said movement of the wire 254 from the position shown in Fig. 13 into the position shown in Fig. 14, so that the spring-loaded setting element 248a is ready for activation as soon as it is released by an actuation of the setting element 248b. Now, when a loose course with loops of a length greater than the length determined by the actuating screw 242b shall be knitted, the setting element 248b is again brought into its active position by the wire 264 in response to a button on the pattern chain. At this time, however, owing to above-mentioned displacement of the wire 254 into the position shown in Fig. 14, the spring-

11

loaded setting element 248a may follow the movement of the lip 250 secured to the setting element 248b until the setting element 248a reaches its active position shown in Fig. 15. Now both latches 244a and 244b are in their active position. However, as the downwardly projecting end of the actuating screw 242a is longer than the downwardly projecting end of the actuating screw 242b, the actuating screw 242a will hit the latch 244a first and thus determine the degree of rocking of the rocking shaft 102. This results in loops of a length larger than the length determined by the actuating screw 242b.

When the loose course has been completed, the setting element 248b is returned from its active position shown in Fig. 15 into its inactive position shown in Fig. 14 by means of the wire 264. At the same time, the setting element 248b takes along the setting element 248a from the active position shown in Fig. 15 into the inactive position shown in Fig. 14 through the medium of the coupling lip 250. At a suitable interval, the wire 254 may be returned from the position shown in Fig. 14 into the position shown in Fig. 13.

The second loose course regulating device 113 (Fig. 1) may be controlled by a controlling cam 280 on the control shaft 180 and by the jack 220h (see Fig. 10).

As best shown in Figs. 1, 16-19, 21 and 24 the rocker wings 54, 56 of the rocker regulating device 120 are rigidly secured by screws 282 to the component 58 of the shifting cam means 58, 60 keyed to the main cam shaft 38. The components 58, 60 of said shifting cam means 58, 60 cooperate with a shifting roller 284 arranged between said components and mounted on a shaft 286 shiftably arranged in suitable bearings of the machine in a manner known per se. Each time, when a narrowing operation shall take place, said shaft 286 and shifting roller 284 are displaced in a manner known per se by means of a mechanism controlled by the pattern chain towards the main cam shaft 38 into the position 286', 284' shown in Fig. 17 so that during the rotation of the main cam shaft 38 the shifting cam means 58 and 60 are shifted to the right into the position 58', 60' in accordance with the shape of the camming surfaces of the shifting cam means 58, 60. Said shifting of the shifting cam means 58' 60 to the right results in a similar shifting of the main cam shaft 38 to the right, owing to the rigid connection between the shifting cam means and said main cam shaft. Of course, at the end of a narrowing operation, the shifting cam means 58, 60 together with the main cam shaft 38 are automatically returned into their original position in accordance with the shape of the camming surfaces of the shifting cam means. Thereafter, the shifting roller 284 and the shaft 286 are automatically retracted into their original position by the controlling mechanism actuated by the pattern chain.

As best shown in Figs. 16, 17, 21 and 24, a roller 288 rotatably and axially immovably arranged on a shaft 290 carried by an upwardly extending arm 292 of a movable braking element 294 is arranged between the hubs of the shifting cam components 58 and 60. The movable braking element 294 is swingably mounted on a shaft 296 carried by a stationary braking element 298 attached to the frame of the machine by screws 300. The hubs of the shifting cam components 58, 60 have a flat surface. Therefore, if the shifting cam components 58, 60 are displaced during a narrowing operation in the manner

12

mentioned above, they will cause a swinging movement of the movable braking element 294 around its pivot 296 through the medium of said roller 288 engaged with the hubs of the shifting cam means.

As best shown in Figs. 21, 24 and 25 the stationary braking element 298 is provided with a friction lining 302 of suitable material. A second stationary braking element 304, likewise, carrying a friction lining 306 is arranged at the opposite side of the movable braking element 294. Said second stationary braking element 304 is connected with the first stationary braking element 298 by means of bolts 308 passing through curved slots 310 of the movable braking element 294. Springs 312 arranged between the heads of the bolts 308 and flanges on the braking element 304 tend to urge the braking elements against each other.

Apparently, above described brake 294, 298, 304 acts as a shock absorber when the main cam shaft 38 is shifted to the right or to the left by means of the shifting device 284, 58, 60.

As best shown in Figs. 1, 16, 20 and 21, the rocker regulating device 120 comprises two blocks 314 and 316 rigidly connected with the regulating shaft 102 by means of pins 318, 320 inserted into registering holes of said blocks and said regulating shaft. A shaft 322 rotatably arranged in bores of said blocks 314 and 316 is rigidly connected by set screws or the like with a first arm 324 and a second arm 326. Said arms 324 and 326 carry a first rod 328 and a second rod 330. A shifting element 332 substantially of the shape best shown in Fig. 26 is slidably arranged on said rods 328 and 330. Said shifting element 332 has two arms 334, 336 embracing a roller 338 slidably and rotatably arranged on the rod 330.

The ball carrying portion 340 of a ball joint 342 is screwed into a threaded bore of the shifting element 332. The other portion of said ball joint 342 is connected to one end of a connecting rod 344 (see Figs. 1 and 16), the other end of which is pivoted at 346 on one arm 348 of a lever 350 swingably mounted on the frame of the machine at 352. The other arm 354 of said lever 350 is pivoted at 356 to one end of a link 358 pivoted at its other end to an extension 360 of a pointex spindle nut 362 engaged in a manner known per se with the pointex spindle 364 rotatably arranged in suitable bearings of the machine. The pointex spindle 364 is automatically rotated at predetermined intervals by a drive (not shown) controlled by the pattern mechanism of the machine.

During the knitting of the welt portions and the leg portion before the knitting of the high heel portions of a stocking blank starts, the pointex spindle nut 362 is in such a position that the roller 338 engaged by the shifting element 332 is placed somewhat to the right of the position shown in Fig. 16 so as to clear the rocker wings 54 and 56. Therefore, during said period the roller 338 is not actuated by the rocker wings 54, 56 and the cam follower 324 is not rocked about its pivot 322.

As soon as during the operation of the machine the pointex spindle 364 is rotated and the pointex spindle nut 362 is displaced in the direction of the horizontal axis of the machine, the shifting element 332 is, likewise, displaced in accordance with the displacement of the pointex spindle nut 362 through the medium of the linkage 358, 350, 344. Thus, the roller 338 is brought

into the path of the rocker wings 54, 56, for example into the position shown in Fig. 16, so that upon an engagement of the rocker wings 54, 56 with said roller 338 the cam follower 324 is rocked about its pivot 322.

The arm 324 has an extension 366 provided with a threaded bore 368. An actuating screw 370 is adjustably threaded into said threaded bore 368. A pointer 372 attached to the extension 366 and arranged for cooperation with a scale 374 arranged on the actuating screw 370 may be used for an accurate adjustment of said actuating screw.

A spring 376 stretched between the rod 112 and the arm 324 tends to urge a lug 378 arranged on said arm against a stop pin 380 carried by the block 314 so as to limit the movement of the arm 324 and, of course, the arm 326 rigidly connected therewith in counter-clockwise direction. Thus, as the movement of the block 314 in counter-clockwise direction is limited by an abutment of the stop screw 110 (see Fig. 2) of the arm 108 against the rod 112, the cam follower arrangement 324, 326, 338 is prevented from falling into the space between the rocker wings 54 and 56.

A spring-loaded latch 382 is swingably and adjustably arranged on a pin 384 carried by the block 314. A spring-loaded setting element 386 rockably arranged on the regulating shaft 102 has a nose 388 for cooperation with said adjustable latch 382 so as to set same in an inactive position out of the path of the actuating screw 370 arranged on the rockable cam follower or in an active position in the path of said actuating screw. The downwardly extending arm of said rockable setting element 386 carries a pin 390 slidably engaged with a slot 392 arranged at one end of a wire 394. The other end of said wire 394 is connected to a cam follower of the type of the cam follower 172 shown in Fig. 9, which is in engagement with a controlling cam 396 (see Fig. 1) keyed to the control shaft 180. The wire 394, furthermore, is under the action of a tension spring 398 stretched between the rod 262 and the free end of the wire 394 (see Figs. 20 and 21). The setting element 386 may be set in alternative inactive and active positions by means of said wire 394 connected to the controlling apparatus shown in Fig. 9 in a manner to be described hereinafter.

Moreover, a controlling element 400 is rockably arranged on the regulating shaft 102. Said controlling element 400 comprises a ring 402 having an abutment 404 for cooperation with a stop pin 406 mounted on the block 314. Furthermore, said ring 402 of the controlling element 400 is provided with a downwardly extending arm 408. A lip 410 secured to said downwardly extending arm 408 by rivets or the like projects from said arm of the controlling element 400 towards the downwardly extending arm of the setting element 386, so that it may engage the latter and act as a coupling element for a purpose to be described hereinafter.

The downwardly extending arm 408 of the controlling element 400 is pivotally connected with one end of a wire 412, the other end of which is pivotally connected at 414 (see Figs. 20, 24 and 25) with an arm 416 of a bell-crank lever 418 swingably mounted on the frame 420. The arm 422 of said bell-crank lever 418 is pivoted at 424 to one end of a connecting rod 426, the other end of which is connected through a ball

joint with the movable braking element 294 described above.

According to Figs. 20, 21, 24 and 25 one end of a connecting rod 428 is pivoted at 430 to the arm 416 of said bell-crank lever 418. The other end of said connecting rod 428 is slidably engaged with a bore 432 arranged at the lower end of a lever 434, the upper end of which is rigidly connected by a set screw 436 with the shaft 322, which is also rigidly connected with the arms 324 and 326 of the cam follower arrangement. A set collar 438 is secured to the free end of the rod 428 for cooperation with the lower end of the lever 434. Thus, a movement of the rod 428 in left-hand direction as viewed in Fig. 20 will cause a rocking of the lever 434 in clockwise direction as soon as the set collar 438 abuts against the surface of the lower end of said lever 434. In such a case, the lever 434 together with the cam follower arrangement 324, 326, 338 will be brought into the position shown in Fig. 21 wherein the roller 338 is out of the path of the rocker wings 54, 56 so that it cannot be actuated by the latter. On the other hand, when the rod 428 remains at a standstill in the position shown in Fig. 20 and the lever 434 rigidly connected with the shaft 322 and the cam follower arrangement 324, 326, 338 is caused to rock owing to a rocking movement of the cam follower arrangement by the rocker wings 54 and 56 or owing to a rocking of the block 314 and regulating shaft 102 caused by a rocking of said regulating shaft 102 by one of the other regulating devices on the machine, the lever 434 may freely perform such rocking movements owing to its loose engagement with the set collar 438.

During the knitting operations when the pointex spindle nut 362 (Fig. 1) is in such a position that the roller 338 of the cam follower arrangement of the rocker regulating device 120 is opposite the rocker wings 54, 56, for example, in the position shown in Fig. 16, and that, consequently, the roller 338 may be engaged by the rocker wings 54, 56, the movable braking element 294 is in the position shown in full lines in Figs. 24 and 25 as long as no narrowing operation takes place. Furthermore, when the length of the loops to be knitted shall be controlled by the rocker regulating device 120, the setting element 386 is automatically set in the position shown in Fig. 20 by the wire 394, so that the latch 382 is in its active position in the path of the actuating screw 370. Each time when a rocker wing 54 or 56 comes into engagement with the roller 338, the arm 324 is rocked about the pivot 322 so that the latch 382 is depressed by the actuating screw 370 and causes a rocking of the regulating shaft 102.

Now, when during the period of the roller 338 of the rocker regulating device 120 being opposite the rocker wings 54, 56 as shown in Fig. 16 a narrowing operation takes place, the main cam shaft 38 is automatically shifted to the right by the shifting means 284, 58, 60 whereby the movable braking element 294 is automatically swung from the full line position shown in Figs. 24 and 25 into the dash and dot line position shown in said figures. This, in turn, causes a rocking of the bell-crank lever 418 from the full line position shown in Fig. 25 into the dash and dot line position shown in said figure with the result that the controlling element 400 and the lever 434 are swung from their position shown in Fig. 20 into the position shown in Fig. 21. Said swinging movement of the controlling element 400 causes,

furthermore, a swinging movement of the setting element 386 by means of the coupling lip 410 from the position shown in Fig. 20 into the position shown in Fig. 21. During said swinging movement of the setting element 386 its pin 398 slides along the slot 392 of the wire 394 which remains in its position. Therefore, the spring-loaded latch 382 is caused by the setting element 386 to move into its inactive position shown in Fig. 21 out of the path of the actuating screw 370. Furthermore, the cam follower arrangement 324, 326, 338 is swung by the lever 434 about its pivot 322 out of engagement with the rocker wings 54, 56. Said swinging of the cam follower arrangement 324, 326, 338 causes a lowering of the actuating screw 370, but this does not result in a rocking of the regulating shaft 102 as the latch 382 is out of the path of the actuating screw 370.

After the completion of such a narrowing operation, the main cam shaft 38 and the movable braking element 294 are automatically returned into their original positions with the result that the bell-crank lever 418 is returned into its original position. Said return movement of the bell-crank lever 418 causes a movement of the rods 412 and 428 in right-hand direction as viewed in Fig. 21. Thus, the controlling element 400 positively connected with the rod 412 is swung in counter-clockwise direction from the position shown in Fig. 21 into the position shown in Fig. 20. Furthermore, the set collar 438 mounted on the rod 428 releases the lever 434, so that the latter together with the cam follower arrangement 324, 326, 338 may be swung in counter-clockwise direction by the spring 376 acting on the cam follower arrangement from the position shown in Fig. 21 into the position shown in Fig. 20 wherein the roller 338 is again in the path of the rocker wings 54, 56. Moreover, the spring acting on the setting element 386 now released by the lip 410 on the controlling element 400 may cause a movement of said setting element 386 from the position shown in Fig. 21 into the position shown in Fig. 20 whereby the latch 392 is again brought into its active position in the path of the actuating screw 370.

Now, if during the period of the roller 338 being opposite the rocker wings 54, 56 as shown in Fig. 16, the rocker regulating device 120 shall be rendered inactive, the wire 394 is automatically brought by the controlling apparatus acting thereon from the position shown in Fig. 20 into the position shown in Fig. 22 whereby the setting element 386 is brought from the position shown in Fig. 20 into the position shown in Fig. 22 with the result that the spring-loaded latch 382 is set into its inactive position out of the path of the actuating screw 370.

Fig. 23 illustrates a position of the controlling element 400 and the setting element 386 when the latter is set by the wire 394 in its inactive position, as shown in Fig. 22 and when at the same time a narrowing operation takes place during which the controlling element 400 is brought into the position shown in Fig. 23 by the rod 412 connected to the bell-crank lever 418 controlled by the movable braking element 294.

As mentioned above, the rocker regulating device 120 is used for controlling the length of the loops knitted in the heel portions 440, 442 and sole portions 444, 446 of a stocking blank 448 (see Fig. 27). At the same time, the instep 450 of the stocking blank 448 is also knitted. The length of the loops of said instep portion 450 shall be smaller than the length of the loops of the heel

portions 440, 442 and sole portions 444, 446. The length of the loops of said inner portion 450 is controlled by controlling means of the main regulating device 116, for example, by the cooperating actuating screw 136c and latch 154c. Therefore, during the knitting of the stocking blank 448 from the point A to the point B said latch 154c of the main regulating device 116 and the latch 382 of the rocker regulating device 120 are in active position. However, as the length of loops in the heel portions 440, 442 and sole portions 444, 446 shall be larger than the length of loops in the inner portion 450, the lower end of the actuating screw 370 is adjusted at a distance 10 from the upper end of the latch 382 which is shorter than the distance between the upper end of the latch 154c and the longer end of the actuating screw 136c. Therefore, during the knitting of a course, the actuating screw 370 will hit the latch 382 first causing a rocking of the regulating shaft 102 through a predetermined angle. Thereafter, when, for example, at the point C the roller 338 of the rocker regulating device 120 may fall into the space between the rocker wings 54, 56, the actuating screw 370 is disengaged from the latch 382 and the regulating shaft 102 may be returned somewhat until the latch 154c of the main regulating device 116 abuts against the actuating screw 136c depressed by the actuation of the cam 46. Thus, the main regulating device 116 controls the length of the loops in a course between the points C and D. When the point D is reached, one of the rocker wings 54, 56 engages again the roller 338, so that the actuating screw 370 hits again the latch 382 causing again a rocking of the regulating shaft 102 through a larger degree as necessary for controlling the length of the loops between the points D and E of a course.

Although the various regulating devices described above are shown as being applied to a two-section straight bar knitting machine, it is understood that the various regulating devices and their controlling mechanisms may also be applied to a straight bar knitting machine having more or less than two sections.

I have described preferred embodiments of my invention, but it is understood that this disclosure is for the purpose of illustration and that various omissions or changes in shape, proportion and arrangement of parts, as well as the substitution of equivalent elements for those herein shown and described may be made without departing from the spirit and scope of the invention as set forth in the appended claims.

What I claim is:

1. In a straight bar knitting machine wherein a rockable regulating shaft is associated with movable needle bars of the machine for controlling the movements thereof so as to regulate the length of loops knitted by the knitting implements of the machine, the combination of: at least one block rigidly connected to the regulating shaft of the machine, at least one latch adjustably mounted on said block, power driven movable actuating means, and automatic controlling means associated with said latch for bringing same at predetermined intervals into alternative positions in and out of the path of said movable actuating means, said actuating means being arranged for displacing said latch so as to cause a rocking of said block and said regulating shaft when the latch is in the path of said actuating means, and said regulating shaft being rockable relative to said controlling means without effecting a displacement of the latter.

2. In a straight bar knitting machine as claimed in claim 1, said controlling means being loosely engaged with said latch.

3. In a straight bar knitting machine wherein a rockable regulating shaft is associated with movable needle bars of the machine for controlling the movements thereof so as to regulate the length of loops knitted by the knitting implements of the machine, the combination of: at least one block rigidly connected to the regulating shaft of the machine, at least one latch adjustably mounted on said block, power driven movable actuating means, adjustable setting means associated with said latch, and an automatic controlling mechanism associated with said setting means for adjusting same at predetermined intervals in alternative positions so as to set said latch in and out of the path of said movable actuating means, said actuating means being arranged for displacing said latch so as to cause a rocking of said block and said regulating shaft when the latch is in the path of said actuating means, said regulating shaft being rockable without effecting a movement of said adjustable setting means.

4. In a straight bar knitting machine wherein a rockable regulating shaft is associated with movable needle bars of the machine for controlling the movements thereof so as to regulate the length of loops knitted by the knitting implements of the machine, the combination of: at least one block rigidly connected to the regulating shaft of the machine, at least one latch adjustably mounted on said block, power driven movable actuating means, adjustable setting means swingably mounted on said regulating shaft, said adjustable setting means being in engagement with said latch, and an automatic controlling mechanism associated with said setting means for adjusting same at predetermined intervals in alternative positions so as to set said latch in and out of the path of said movable actuating means, said actuating means being arranged for displacing said latch so as to cause a rocking of said block and said regulating shaft when the latch is in the path of said actuating means, and said regulating shaft being rockable without effecting a movement of said adjustable setting means swingably mounted thereon.

5. In a straight bar knitting machine wherein a rockable regulating shaft is associated with movable needle bars of the machine for controlling the movements thereof so as to regulate the length of loops knitted by the knitting implements of the machine, the combination of: a series of blocks rigidly connected to the regulating shaft of the machine, at least one latch adjustably mounted on each of said blocks, a series of power driven movable actuating means, and a plurality of automatic controlling means, each of said automatic controlling means being associated with such a latch for selectively bringing same at predetermined intervals into alternative positions in and out of the path of such a movable actuating means, said actuating means being arranged for displacing such an associated latch so as to cause a rocking of such a block and said regulating shaft when said associated latch is in the path of such an actuating means, and said regulating shaft being rockable relative to said controlling means without effecting a displacement of the latter.

6. In a straight bar knitting machine wherein a rockable regulating shaft is associated with movable needle bars of the machine for controlling the movements thereof so as to regulate the

length of loops knitted by the knitting implements of the machine, the combination of: a series of blocks rigidly connected to the regulating shaft of the machine, at least one latch adjustably mounted on each of said blocks, a series of power driven movable actuating means, a plurality of adjustable setting means rockably mounted on said regulating shaft, each of said adjustable setting means being in engagement with such a latch, and a plurality of automatic controlling mechanisms, each of said automatic controlling mechanisms being associated with such a setting means for selectively adjusting same at predetermined intervals in alternative positions so as to set such a latch in and out of the path of such a movable actuating means, said actuating means being arranged for displacing such an associated latch so as to cause a rocking of such a block and said regulating shaft when said associated latch is in the path of such an actuating means.

7. In a straight bar knitting machine wherein a rockable regulating shaft is associated with movable needle bars of the machine for controlling the movements thereof so as to regulate the length of loops knitted by the knitting implements of the machine, the combination of: a block rigidly connected to the regulating shaft of the machine, a plurality of latches adjustably mounted on said block, a power driven rotatable shaft, a cam secured to said shaft, a swingable cam follower arranged for co-operation with said cam, a plurality of actuating members connected to said cam follower, each of said actuating members being arranged for cooperation with one of said latches, and a plurality of automatic controlling means, each of said automatic controlling means being associated with such a latch for selectively bringing same at predetermined intervals into alternative positions in and out of the path of such an associated actuating member, each of said actuating members being arranged for displacing its associated latch so as to cause a rocking of said block and said regulating shaft when said associated latch is in the path of such an actuating member.

8. In a straight bar knitting machine as claimed in claim 7, said cam follower being swingably mounted on said block.

9. In a straight bar knitting machine as claimed in claim 7, said actuating members being adjustably arranged on said cam follower.

10. In a straight bar knitting machine wherein a rockable regulating shaft is associated with movable needle bars of the machine for controlling the movements thereof so as to regulate the length of loops knitted by the knitting implements of the machine, the combination of: a block rigidly connected to the regulating shaft of the machine, a plurality of latches adjustably mounted on said block, a power driven rotatable shaft, a cam secured to said shaft, a swingable cam follower arranged for co-operation with said cam, a plurality of actuating members connected to said cam follower, each of said actuating members being arranged for cooperation with one of said latches, a plurality of adjustable setting means rockably mounted on said regulating shaft, each of said adjustable setting means being in engagement with such a latch, and a plurality of automatic controlling mechanisms, each of said automatic controlling mechanisms being associated with such a setting means for selectively adjusting same at predetermined intervals in alternative positions so as to set such a latch in and out of the path of such an asso-

ciated actuating member, each of said actuating members being arranged for displacing its associated latch so as to cause a rocking of said block and said regulating shaft when said associated latch is in the path of such an actuating member.

11. In a straight bar knitting machine as claimed in claim 10, said cam follower being swingably mounted on said block.

12. In a straight bar knitting machine wherein a rockable regulating shaft is associated with movable needle bars of the machine for controlling the movements thereof so as to regulate the length of loops knitted by the knitting implements of the machine, the combination of: a block rigidly connected to the regulating shaft of the machine, a first latch adjustably mounted on said block, a second latch adjustably mounted on said block, a power-driven rotatable shaft, a cam secured to said shaft, a swingable cam follower arranged for cooperation with said cam, a first actuating member connected to said cam follower and arranged for cooperation with said first latch, a second actuating member connected to said cam follower and arranged for cooperation with said second latch, a first setting means rockably mounted on said regulating shaft and engaged with said first latch, a second setting means rockably mounted on said regulating shaft and engaged with said second latch, said first and second setting means being adjustable in an inactive position wherein they set the associated latch out of the path of the associated actuating member and in an active position wherein they set the associated latch in the path of the associated actuating member, an automatic preselector associated with said second setting means for releasing same at predetermined intervals for adjustments, and an automatic controlling mechanism associated with said first and second setting means for adjusting at predetermined intervals the first setting means and the second setting means, when the latter is released, in alternative active and inactive positions, each of said actuating members being arranged for displacing its associated latch so as to cause a rocking of said block and said regulating shaft when said associated latch is in the path of such an actuating member.

13. In a straight bar knitting machine as claimed in claim 12, said cam follower being swingably mounted on said block.

14. In a straight bar knitting machine wherein a rockable regulating shaft is associated with movable needle bars of the machine for controlling the movements thereof so as to regulate the length of loops knitted by the knitting implements of the machine, the combination of: a block rigidly connected to the regulating shaft of the machine, a first latch adjustably mounted on said block, a second latch adjustably mounted on said block, a power driven rotatable shaft, a cam secured to said shaft, a swingable cam follower arranged for cooperation with said cam, a first actuating member connected to said cam follower and arranged for cooperation with said first latch, a second actuating member connected to said cam follower and arranged for cooperation with said second latch, a first setting means rockably mounted on said regulating shaft and engaged with said first latch, a second setting means rockably mounted on said regulating shaft and engaged with said second latch, said first and second setting means being adjustable in an inactive position wherein they set the associated latch out of the path of the associated actuating

member and in an active position wherein they set the associated latch in the path of the associated actuating member, a power driven pattern chain, a controlling apparatus actuated by said pattern chain, a preselector actuated by said controlling apparatus and associated with said second setting means for releasing same at predetermined intervals for adjustments, and a controlling mechanism actuated by said pattern chain and associated with said first and second setting means for adjusting at predetermined intervals the first setting means and the second setting means, when the latter is released, in alternative active and inactive positions, each of said actuating members being arranged for displacing its associated latch so as to cause a rocking of said block and said regulating shaft when said associated latch is in the path of such an actuating member.

15. In a straight bar knitting machine wherein a rockable regulating shaft is associated with movable needle bars of the machine for controlling the movements thereof so as to regulate the length of loops knitted by the knitting implements of the machine, the combination of: a block rigidly connected to the regulating shaft of the machine, a first latch adjustably mounted on said block, a second latch adjustably mounted on said block, a power-driven rotatable shaft, a cam secured to said shaft, a swingable cam follower arranged for cooperation with said cam, a first actuating member connected to said cam follower and arranged for cooperation with said first latch, a second actuating member connected to said cam follower and arranged for cooperation with said second latch, a first setting means rockably mounted on said regulating shaft and engaged with said second latch, a first automatic controlling mechanism associated with said first setting means for adjusting same at predetermined intervals in alternative positions so as to set said first latch in and out of the path of the first actuating member, an automatic disengageable coupling between said first and second setting means, and a second automatic controlling mechanism associated with said second setting means for normally holding same in a position wherein it sets said second latch out of the path of the second actuating member and for releasing same at predetermined intervals so as to permit a displacement of said second setting means into a position wherein it sets said second latch in the path of the second actuating member in response to a similar displacement of the coupled first setting means, each of said actuating members being arranged for displacing its associated latch so as to cause a rocking of said block and said regulating shaft when said associated latch is in the path of such an actuating member.

16. In a straight bar knitting machine wherein a rockable regulating shaft is associated with movable needle bars of the machine for controlling the movements thereof so as to regulate the length of loops knitted by the knitting implements of the machine, the combination of: a block rigidly connected to the regulating shaft of the machine, a first latch adjustably mounted on said block, a second latch adjustably mounted on said block, a power driven rotatable shaft, a cam secured to said shaft, a swingable cam follower arranged for cooperation with said cam, a first actuating member connected to said cam follower and arranged for cooperation with said first latch, a second actuating

ating member connected to said cam follower and arranged for cooperation with said second latch, a first setting means rockably mounted on said regulating shaft and engaged with said first latch, a second setting means rockably mounted on said regulating shaft and engaged with said second latch, a power driven pattern chain, a first controlling mechanism actuated by said pattern chain and associated with said first setting means for adjusting same at predetermined intervals in alternative positions so as to set said first latch in and out of the path of the first actuating member, an automatically disengageable coupling between said first and second setting means, a controlling apparatus actuated by said pattern chain, and a second controlling mechanism actuated by said controlling apparatus and associated with said second setting means for normally holding same in a position wherein it sets said second latch out of the path of the second actuating member and for releasing same at predetermined intervals so as to permit a displacement of said second setting means into a position wherein it sets said second latch in the path of the second actuating member in response to a similar displacement of the coupled first setting means, each of said actuating members being arranged for displacing its associated latch so as to cause a rocking of said block and said regulating shaft when said associated latch is in the path of such an actuating member.

17. In a straight bar knitting machine as claimed in claim 15, a coupling element secured to one of said setting means and loosely contacting the other setting means, a spring acting on said second setting means and tending to hold the coupling element engaged with the contacting setting means, and a pin-and-slot connection between said second setting means and said second controlling mechanism.

18. In a straight bar knitting machine wherein a rockable regulating shaft is associated with movable needle bars of the machine for controlling the movements thereof so as to regulate the length of loops knitted by the knitting implements of the machine, the combination of: a block rigidly connected to the regulating shaft of the machine, a latch adjustably mounted on said block, a power driven shaft, said shaft being rotatable and shiftable, a rocker wing secured to said shaft, a swingable cam follower arranged for cooperation with said rocker wing, an actuating member connected to said cam follower and arranged for cooperation with said latch, a setting means rockably mounted on said regulating shaft and engaged with said latch, a first controlling mechanism associated with said setting means for adjusting same at predetermined intervals in alternative positions so as to set said latch in and out of the path of said actuating member, said actuating member being arranged for displacing said latch so as to cause a rocking of said block and said regulating shaft when said latch is in the path of said actuating member, automatic shifting means associated with said shaft for shifting same into a narrowing operation position at predetermined intervals, and a second controlling mechanism associated with said cam follower and said setting means, said second controlling mechanism being responsive to a shifting operation of said shifting means and being arranged for swinging said cam follower out of the path of said rocker wing and for moving said setting means into a position

wherein it sets the latch out of the path of the actuating member when the shaft is shifted into its narrowing operation position.

19. In a straight bar knitting machine as claimed in claim 18, said cam follower being swingably mounted on said block.

20. In a straight bar knitting machine wherein a rockable regulating shaft is associated with movable needle bars of the machine for controlling the movements thereof so as to regulate the length of loops knitted by the knitting implements of the machine, the combination of: a block rigidly connected to the regulating shaft of the machine, a latch adjustably mounted on said block, a power driven shaft, said shaft being rotatable and shiftable, a rocker wing secured to said shaft, a swingable cam follower arranged for cooperation with said rocker wing, an actuating member connected to said cam follower and arranged for cooperation with said latch, a setting means rockably mounted on said regulating shaft and engaged with said latch, a first controlling mechanism associated with said setting means for adjusting same at predetermined intervals in alternative positions so as to set said latch in and out of the path of said actuating member, said actuating member being arranged for displacing said latch, so as to cause a rocking of said block and said regulating shaft when said latch is in the path of said actuating member, automatic shifting means associated with said shaft for shifting same into a narrowing operation position at predetermined intervals, a brake including relatively movable braking members associated with said shiftable shaft, a movable braking member of said brake being connected with said shaft so as to participate in shifting movements thereof, and a second controlling mechanism associated with said cam follower and said setting means, said second controlling mechanism being connected to said movable braking member and being arranged for swinging said cam follower out of the path of said rocker wing and for moving said setting means into a position wherein it sets the latch out of the path of the actuating member when the shaft is shifted into its narrowing operation position.

21. In a straight bar knitting machine as claimed in claim 20, a controlling member rockably mounted on said regulating shaft, a disengageable coupling arranged between said controlling member and said setting means, and a pin-and-slot connection between said setting means and said controlling mechanism.

22. In a straight bar knitting machine as claimed in claim 3, such a power driven movable actuating means including a power driven rotatable shaft, cam means secured to said shaft, a cam follower swingably mounted on said block, said cam follower cooperating with said cam means, and an actuating member on said cam follower for cooperation with said latch.

23. In a straight bar knitting machine as claimed in claim 22, said actuating member being adjustably mounted on said cam follower.

24. In a straight bar knitting machine wherein a rockable regulating shaft is associated with movable needle bars of the machine for controlling the movements thereof so as to regulate the length of loops knitted by the knitting implements of the machine, the combination of: at least one block rigidly connected to the regulating shaft of the machine, at least one latch mounted on said block, power driven movable

actuating means arranged for movement along a predetermined path, said latch being settable relative to said block into alternative positions in and out of the path of said movable actuating means, and automatic controlling means associated with said latch for setting same at predetermined intervals into one of said alternative positions, said actuating means being arranged for abutting engagement with said latch when the latter is in the path of said actuating means whereby upon an abutting engagement of said actuating means with said latch the latter is displaced together with said block so as to cause a rocking of said block and said regulating shaft, and said regulating shaft being rockable relative to said controlling means without effecting a displacement of the latter.

25. In a straight bar knitting machine as claimed in claim 24, said controlling means being loosely engaged with said latch.

26. In a straight bar knitting machine wherein a rockable regulating shaft is associated with movable needle bars of the machine for controlling the movements thereof so as to regulate the length of loops knitted by the knitting implements of the machine, the combination of a series of blocks rigidly connected to the regulating shaft, at least one latch mounted on each of said blocks, a series of power driven movable actuating means arranged for movement along predetermined paths, each of said latches being settable relative to the associated block into alternative positions in and out of the path of such a movable actuating means, and a plurality of automatic controlling means, each of said automatic controlling means being associated with such a latch for setting same at predetermined intervals into one of said alternative positions, said actuating means being arranged for abutting engagement with such an associated latch when the latter is in the path of said actuating means whereby upon an abutting engagement of said actuating means with said latch the latter is displaced together with the associated block so as to cause a rocking of said block and said regulating shaft, and said regulating shaft being rockable relative to said controlling means without effecting a displacement of the latter.

27. In a straight bar knitting machine wherein a rockable regulating shaft is associated with movable needle bars of the machine for controlling the movements thereof so as to regulate the length of loops knitted by the knitting implements of the machine, the combination of: at least one block rigidly connected to the regulating shaft of the machine, at least one latch adjustably mounted on said block, a power-driven rotatable shaft, cam means secured to said shaft,

a cam follower swingably mounted on said block, said cam follower cooperating with said cam means, an actuating member arranged on said cam follower for cooperation with said latch, and automatic controlling means associated with said latch for bringing same at predetermined intervals into alternative positions in and out of the path of said movable actuating means, said actuating member being arranged for displacing said latch so as to cause a rocking of said block and said regulating shaft when the latch is in the path of said actuating member.

28. In a straight bar knitting machine as claimed in claim 27, said actuating member being adjustably mounted on said cam follower.

29. In a straight bar knitting machine wherein a rockable regulating shaft is associated with movable needle bars of the machine for controlling the movements thereof so as to regulate

20 the length of loops knitted by the knitting implements of the machine, the combination of: at least one block rigidly connected to the regulating shaft of the machine, at least one latch mounted on said block, a power-driven rotatable

25 shaft, cam means secured to said shaft, a cam follower swingably mounted on said block, said cam follower cooperating with said cam means, an actuating member arranged on said cam follower for movement along a predetermined

30 path and for cooperation with said latch, said latch being settable relative to said block into alternative positions in and out of the path of said movable actuating member, and automatic controlling means associated with said latch for

35 setting same at predetermined intervals into one of said alternative positions, said actuating member being arranged for abutting engagement with said latch when the latter is in the path of said actuating member whereby upon an abutting en-

40 gagement of said actuating member with said latch the latter is displaced together with said block so as to cause a rocking of said block and said regulating shaft.

30. In a straight bar knitting machine as claimed in claim 29, said actuating member being adjustably mounted on said cam follower.
